UNITED STATES PATENT OFFICE.

THOMAS JOHN WOODWARD, OF BIRMINGHAM, ENGLAND, ASSIGNOR
TO CHANCE BROTHERS AND CO., LIMITED, OF WEST SMETHWICK,
ENGLAND.

DESIGN FOR AN ORNAMENTAL TILE.

SPECIFICATION forming part of Design No. 35,774, dated February 25, 1902.

Application filed January 10, 1902. Serial No. 89,235. Term of patent 14 years.

To all whom it may concern:

Be it known that I, THOMAS JOHN WOODWARD, a subject of the King of Great Britain, residing at New Eldon Chambers, Cherry 5 street, Birmingham, England, have invented and produced a new and original Design for an Ornamental Tile, of which the following is a specification.

The drawing represents the face view of a 10 tile ornamented with my design and also a cross-section of the same, taken on the dotted line $\alpha\alpha$.

The design, which is in low relief or intaglio, as shown by the section, is composed of a filling and border made up as follows: The filling 15 consists of daisy patterns aaa on a ground of berries or hemispherical projections b , inclosed by scrolls ddd , with volute-like ends e , from which volute-like ends anthemions c

spring. The border is made up of plain bands 20 or fillets fg , with long scroll-like forms h , terminating in volute ends, from which an anthemion i springs. At the middle of each long scroll h is a plain band k , with volute ends ll , which bind in a panel which is filled 25 with hemispherical projections m .

Having described my invention, what I claim as new, and desire to secure by Letters Patent, is—

The design for a tile as herein shown and 30 described.

In testimony whereof I have hereunto set my hand in presence of two subscribing witnesses.

THOMAS JOHN WOODWARD.
